UNITED STATES PATENT OFFICE.

JOSEPH H. MACZUBA, OF PASSAIC, NEW JERSEY, ASSIGNOR TO SHAPIRO & SON CO., INC., OF NEW YORK, N. Y., A CORPORATION OF NEW YORK.

DESIGN FOR A TEXTILE FABRIC.

Application filed April 4, 1924. Serial No. 9,157. Term of patent 3½ years.

To all whom it may concern:

Be it known that I, JOSEPH H. MACZUBA, a citizen of the United States, residing at Passaic, in the county of Passaic, State of New Jersey, have invented a new, original, and ornamental Design for Textile Fabric, of which the following is a specification, reference being had to the accompanying drawing, forming part thereof.

The figure is a plan view of a textile fabric showing my new design.

I claim:

The ornamental design for a textile fabric substantially as shown.

JOSEPH H. MACZUBA.
